CHAIN GUARD AND FENDER BRACE COMBINATION FOR A BICYCLE OR THE LIKE

Charles A. McLeod, Birmingham, Mich., assignor to
Evans Products Company, Plymouth, Mich., a corpora-
tion of Delaware

Filed Mar. 7, 1960, Ser. No. 59,623

Term of patent 14 years

(Cl. D90—5)

FIGURE 1 is a front perspective view of a chain guard and fender brace combination for a bicycle or the like showing my new design;

FIGURE 2 is a top plan view thereof on an enlarged scale;

FIGURE 3 is a front elevation thereof as shown in FIGURE 2;

FIGURE 4 is a bottom plan view thereof as shown in FIGURE 2; and

FIGURES 5 and 6 are vertical cross-sectional views thereof on a further enlarged scale taken, respectively, along the lines 5-5 and 6-6 of FIGURE 3.

The broken line representation of a bicycle in FIGURE 1 is for purposes of illustration only.

I claim:

The ornamental design for a chain guard and fender brace combination for a bicycle or the like, as shown and described.
